UNITED STATES PATENT OFFICE.

HENRY LABIS, OF MOUSCRON, BELGIUM.

STOP MOTION FOR TWISTING MACHINES.

Application filed June 27, 1922. Serial No. 571,232.

To all whom it may concern:

Be it known that I, HENRY LABIS, a subject of the King of Belgium, and resident of Monscron, Belgium, have invented certain new and useful Improvements in and Relating to Stop Motions for Twisting Machines, of which the following is a specification.

My present invention relates to an improved stop-motion for thread twisting machines, whereby the thread coming from the spool on the creel will be stopped in case of its break at any point of its course. The stop of the thread may be effected according to my invention by means of any desired blade or the like, interposing between the pressure roller and the drawing roller between which the thread is moved, the pressure roller being thus raised above the drawing roller so that the thread will no longer be carried away.

An essential feature of my improved device resides in its great simplicity; it does not comprise complicated parts or mechanisms, nor springs or the like.

Another feature is the instantaneous stop of the thread to be twisted, which stop is caused by the action of a part on the thread and not on the drawing roller, which continues its rotation.

The invention is illustrated by way of example in the accompanying drawing, wherein:

Fig. 1 is a diagrammatical view of the working parts of a twisting machine element, showing the course of the thread from the spool on the creel to the twining spool, the machine being in normal operation.

Fig. 2 is a similar view showing the various parts in their positions after the break of the thread.

My present device is applicable to any system of twisting loom, either with wings, slider, needles or the like.

The thread 1 wound off the spool 2 on the creel is first moved through the thread-guide 3, then around the pressure roller 4 arranged above the drawing roller 5 and around the pillar 6 to pass again between the pressure roller 4 and drawing roller 5. Then the thread is moved through the eyelet 8 of my device and the thread-guide 9 and slider 10 to the twining spool 7.

My improved device comprises a body portion 11 serving to attach the same to the frame 12 of the loom, and a part of particu-

lar shape, pivotally connected at 13 to the body portion 11. Said part is formed of two portions: a lower portion 14 ending into the eyelet 8 and rigidly connected at the pivot pin 13 to the upper portion 15. The latter carries a pin to which is pivotally connected a projection 16. Secured to the latter in any desired way is a blade 17, held in horizontal position by any desired means (not shown).

The constitution of this part of my improved device has been described and shown merely by way of example and shall not limit my invention. The number and shape of the parts may be varied, and the projection 16, for instance, may be avoided and the blade 17 directly connected to the pin of the portion 15. Again the portions 14 and 15 may be made of a single piece.

In normal operation (Fig. 1) the thread 1 passing through the eyelet 8 produces a tension or drag on the lower portion 14, whereby the upper portion 15 will be held vertically against the frame 12. If a break of thread occurs, the portion 14 which is no longer sustained, will drop into the position shown in Fig. 2, the weight of said portion causing the blade 17 to be moved horizontally below the thread 1 and between the pressure roller 4 and the drawing roller 5, said blade thus raising the pressure roller 4 somewhat above the drawing roller 5 in its bearings 18. In this way, the thread 1 will no longer be in contact with the drawing roller 5 and therefore stopped.

If the thread breaks between the eyelet 8 and the guide 9 or the spool 7, the thread will be brought back (Fig. 2) whereby the end of the thread will be prevented from being carried away by one of the adjacent twining members, which occurs frequently in other known arrangements. If on the contrary the break of thread occurs above the eyelet 8, the floating end of thread cannot be engaged and carried away by a moving part, the blade 17 and the pressure roller 4 retaining the thread.

Therefore my improved arrangement has the advantages of great simplicity in construction, operation and application; immediate stop of the thread if a break occurs; absolute reliability in operation, requiring no adjusting of springs, no manipulation for starting the element after the break of a thread, and entangling of threads is impossible at the moment a break occurs.

Having now fully described my said invention, what I claim and desire to secure by Letters Patent is:

An improved stop motion for thread twisting machines, comprising a body portion adapted to encircle a frame bar of the machine, a rigidly formed angularly related two-part member mounted on said body portion, one of said parts being similarly curved 5 to the drawing roller and having its terminal eye arranged below said roller, the upper part being substantially coextensive in length with that of the body portion, the member being pivotally connected at the juncture of its parts to the lower end of 10

said body portion, and a blade pivotally connected to the upper end of said upper part of said member, said upper part of the member moving into contact with and limited in movement by said body portion to 20 define and position the blade in its inoperative position relative to the roller, whereby the operative movement of the blade is the same under all conditions.

Dated this 7th day of June, 1922.

HENRY LABIS.
